BATTERY BROODER

William M. Willett, George T. Markey, and John B. Olson, Fort Atkinson, Wis., assignors to James Manufacturing Company, Fort Atkinson, Wis., a company of Wisconsin

Application July 5, 1940, Serial No. 344,110

7 Claims. (Cl. 119—32)

The present invention relates to battery brooders and has for its principal object, the use of gas as a heating medium for the hover.

A further object of the present invention is to provide a hover wherein electric resistors may be economically used for heating the hover.

Another object of the present invention is to provide a hover having new and novel means whereby it may be conveniently raised and lowered and whereby a transverse division wall may be provided wherein a single hover will serve two separate chambers.

A still further object of the present invention is to provide novel counterbalancing means for the hover whereby the hover may be quickly and easily moved to any desired height and whereby when moved into position, it will remain in the selected position.

Another object of the present invention is to provide novel gas heating means and a novel outlet for the products of combustion.

It is an object of the present invention to provide means whereby the hovers may be easily adjusted vertically by means of a cranked screw but having a supplemental temporary lifting means which does not affect the normal vertically adjusted position of the hover.

Another object of the present invention is to provide means whereby a single longitudinally centrally positioned burner may be used in an elongated hover having means whereby the heat radiating downwardly from the hover is equally distributed.

One of the objects of the present invention is to provide a battery brooder comprising a number of compartments, one above the other, the lower compartment being spaced a distance from the floor and having means therearound to isolate the space under the lower compartment or between this compartment and the floor.

To these and other useful ends, our invention consists of parts, combinations of parts, or their equivalents, and mode of operation, as herein-after set forth and claimed and shown in the accompanying drawings in which:

Fig. 1 is a perspective view of my improved brooder, the hovers being arranged for burning gas as the heating medium and having several of the side and end walls removed so as to more clearly show the position of the hovers.

Fig. 2 is a transverse end section of the hover, taken on line 2—2 of Figure 7.

Fig. 3 is a reduced bottom view of the hover.

Fig. 4 is an enlarged end view of one of the

compartments with a fraction of the watering trough removed.

Fig. 5 is a fractional sectional view of our improved device, taken on line 5—5 of Figure 4.

Fig. 6 is an enlarged bottom view of the gas burner.

Fig. 7 is an enlarged top view of the hover, illustrating the means for regulating the height of the same.

10 Fig. 8 is a side view of the hover as illustrated in Figure 7.

As thus illustrated, the battery, in its entirety, is designated by reference character A, the hovers are designated, in their entireties, by reference characters B, and the chimney in its entirety by reference character C.

Member A comprises preferably, four corner posts 10 having suitable transverse members 11 which act to hold posts 10 in transverse spaced relation, and provide divisions between the compartments.

We provide longitudinal members 12 which act to hold posts 10 in longitudinal spaced relation and form divisions between the compartments, thus forming a rigid frame which obviously may include one or more compartments.

The wall of the compartments are formed in a manner too well known to require further description or illustration. One form of end wall 30 is clearly indicated in Figure 4 and another form of side walls or panels is shown in Figure 1. The shapes of the water and feed hoppers are too well known to require further illustration or description. The watering troughs may be as illustrated in Figure 4 or on the left end of Figure 5. The feed troughs are shaped preferably as illustrated on the near side of Figure 1. The watering and feeding troughs generally are positioned relative to the screen floor of each compartment as illustrated in these figures. That is, the bottoms of these troughs will be about on the horizontal plane of floor screens 54. In all standard brooders, it is the custom to place the troughs on the outside of the walls of the compartment.

40 These walls or wire panels are frequently made adjustable so as to provide suitable access to the troughs and means whereby the attendant may refill the troughs from the exterior of the device. The lower compartment, which will hereinafter 45 be called number one compartment, for obvious reasons must be spaced a short distance above the floor. In order to protect the space under the compartments from drafts and prevent the accumulation of dirt which would require constant cleaning, we provide side and end panels

50 55

14 and 15, these panels being secured to corner posts 10 at their ends and being adapted to enclose the space directly below the droppings pan in the number one compartment and the floor. Thus, a dead air space is provided and chicks that escape from the compartments will not be able to get under number one compartment.

Members B preferably occupy about one half the horizontal space in the compartments and are arranged to be heated and adjusted vertically, as will hereinafter appear. Members B consist of gable roofs 20, which are insulated as illustrated and are provided with inturned edges 21 and 22 (see Figure 2) and end walls 23.

End walls 23, at their bottom edges, are positioned slightly above the upper edges of members 22 and a bottom or floor plate 24 is moved into position drawer-like from one end of the device. At one end of members B and in walls 23, we provide an opening as at 25 suitable for the reception of an outlet duct 26. Ducts 26 are made large enough to permit the escape of the products of combustion from the hovers into chimney C and are formed with a lapped joint as at 27, the lap being cut away at the ends for a short distance so the duct ends will enter openings 25 and similar openings in member C.

Ducts 26 fit loosely into the openings in members 23 and C. It will be noted that members 26 are slightly higher on their chimney ends. However, the cut-away portions of laps 27 and lengths of members 26 are adapted to permit members B to be raised or lowered to their extreme positions without becoming detached or binding.

It will be seen, that we have provided adequate chimney outlets for members B. Chimney C is firmly held to member A in any suitable manner. We have shown this fastening being accomplished by means of a U-strap 28 and additional anchors 30—30, the lower end of member C being closed and the upper end being adapted to be extended to a conventional chimney or through the roof of the building.

Brooders of this class are adapted to be housed and generally the inclosure is heated to a moderate temperature so as to make it more convenient and economical to heat the compartments suitably for chicks at various ages.

We will now describe our preferred means for heating member B. We provide an opening 35 in roof member 20 large enough to receive the gas burner which comprises an inverted U-shaped bracket 36 adapted to cover this opening. Opening 35 is large enough to receive the spreader plate 37 of the burner which is secured to the inner end of a bracket 38 the bracket being fastened to member 36, as illustrated in the various figures.

Bracket 38 is provided with a burner holding extension 39, the burner comprising a member 40 having suitable means for a connection to the hose 41 and extending through an opening in the lower end of member 39 (see Figure 2) and being suitably held thereto by means of a nut 42.

The burner is provided with a mixer pint and jet and an air regulating screw 44. The outlet end of the burner is provided with a circular disc 46 which is positioned near the end of member 40 so as to act as a shield against the direct radiation of heat from the flame into the burner parts.

Members 36 and 40 are adapted to largely close openings 35 and be attached to member 20 by

means of bolts 48. When the burner is attached, member 37 will be in the position as shown in Figure 2.

When the burner is properly adjusted, the flame extends into the hover, the bulk of the flame being directly under member 37, this member acting as a spreader for the flame. It will be noted that member 24 is detachably secured to the hover and, in addition to having a transverse extension 50 secured to its longitudinal center, it is suitably painted at its ends on opposite sides as at 49, the paint extending from the ends to lines as at 51. Without these ends being painted as described, the heat is not evenly distributed; but, when painted, because of the action of the paint, the heat is suitably distributed under the hover and this feature is considered to be one of the elements of the present invention. It has been found in practice, that a thin coat of black enamel paint best answers the purpose, the paint acting to transfer additional heat from the interior of the hover downwardly to the space directly thereunder.

It will be understood that when an on and off device is provided for regulating the heat, a pilot light may be supplied or the heat may be regulated by controlling the size of the flame by well known means.

It will be seen that there is considerable room under and around the edges of the hover for maintaining suitable temperature for the birds and that when the birds desire a cooler temperature, they have four sides around the hover to which they may go.

We provide means for regulating the height of member B in the following manner:

End members 23 extend slightly above the apex of members 20 (see Figure 8) and we secure, to the top of these members, preferably, a rubberoid or fabric cloth 60 as at 61 in any suitable manner. We provide stationary transverse bars 62—62 which are positioned about in a vertical plane with members 23 and high enough to permit the hover to move to its highest position, cloth 60 being bent around member 62, each cloth member extending in the same direction and having secured to their ends, sheet metal pieces 63 and 64. Clearly by moving members 63 and 64 to the right or left, the hover will be raised or lowered.

We provide a shaft 65, the inner end being screw threaded into a nut 66 on member 63, which is held against end movement by opening 67 in member 63. The other end of member 65 is secured to member 64 and nut 66 may be used for raising or lowering its end of the hover relative to the other end.

We provide a shaft 69 which is screw threaded into a nut 68 and slidably extends through a plate 70, thus forming a support for the outer end of member 69. Shaft 69 has a cranked extension as at 71, and a right angle portion being adapted to rest against plate 70 thus, by turning crank 71, members 60 will be moved in one direction or the other, so as to raise or lower the hover.

To facilitate the raising and lowering operations of the hover, we provide a spring 75 which is secured to member 63, at one end, and to a chain 76 at the other end, the chain passing through a key opening 77 in plate 70 (see Figure 4). Thus, clearly, by moving the chain to the large part of the key opening, it may be pulled in one direction or the other so as to put more or less tension on spring 75.

Spring 75 is designed to exactly balance the

hover; therefore the friction of members 60 around members 62 will be enough to hold the hover in whatever position it is placed.

Spring 75 may be adjusted so the tendency of the hover will be to move downwardly, thus to hold crank 71 against plate 70. Therefore, by turning the crank, close vertical adjustments of the hover may be secured. If, however, it is desired to lift the hover temporarily, so as to bring all of the birds fully into view, all that is necessary is to pull on crank 71 and, when desired, the crank may be pushed back or allowed to return to its original position.

It will be seen that close adjustments may be secured as to the height of the hover. The ends of the hover may be adjusted to an equal height and the entire hover may be conveniently and quickly raised to any desired height. All of these adjustments clearly may be accomplished without interfering in the least with the connection of the hover to chimney C.

Generally, it is desired that the hover serve two compartments. This is accomplished by means of plate 50 and brackets 52-52. These members are spaced and deep enough so when member B is in its highest position, the birds will not be able to pass from one compartment to the other.

Brackets 52 extend from one side panel of the compartment to the other and are shaped as clearly illustrated in Figure 8, having ledges which act as supports for the wire screen floor 54 and droppings pan 55. Somewhat similar devices are furnished at the ends of the battery so members 54 and 55 may be removed and replaced drawerlike transverse to the battery (see Figure 5).

We provide partitions 53 on opposite sides of member B which rest between members 52 and extend upwardly far enough to prevent the chicks from moving from one end of the compartment to the other. We provide partitions 56 which are secured to the top of hovers B, filling the space between partitions 53.

It will be seen that we have provided a battery brooder adapted to be heated by gas. When it is desired to heat the hover by means of electric current, then suitable resistance pads may be provided in place of the gas burner. When gas is used, it will be seen that none of the products of combustion will be permitted to escape into the compartments, and when the hover is heated electrically, if desired, chimney connections 26 may be closed or dispensed with so as to avoid wasting heat.

Chimney C will create a slight vacuum in members B. In addition to permitting all of the products of combustion to escape, a slight amount of air will be drawn into the hover and will escape with the products of combustion; therefore the air around the hover will be kept fresh at all times.

In Figures 1, 2 and 4, the burners are shown as being on the right side of the hovers when viewed from the chimney end of the brooder. In Figure 7, the burner is on the other side of the hover. We reserve the right to place this burner on either side of the hover.

Clearly our device may be easily understood and conveniently operated because the operator will have complete control of the position of the hover and of the heat.

Having thus shown and described our invention, we claim:

1. A brooder of the class described, comprising

a compartment having medially positioned therein a hover and means whereby the hover may be raised and lowered manually, a gas burner mounted medially on said hover, a flame spreader plate within the hover and adapted to lie over and spread the flame transversely, and a chimney positioned adjacent one end of said compartment and having a duct connection to said hover, means on said duct connection adapted to limit its longitudinal movement.

2. A device as recited in claim 1 including; said hover having a gable roof and a sheet metal floor adapted to be removed and replaced drawer-like.

3. A brooder of the class described, comprising an elongated compartment having an elongated medially positioned hover therein and means whereby the hover may be raised and lowered manually, a gas burner mounted medially longitudinally on said hover, a flame spreader plate within the hover and adapted to lie over and spread the flame transversely, said hover having a longitudinally gable shaped roof, and a sheet metal floor adapted to be removed and replaced longitudinally drawer-like, the ends of said floor for a distance on opposite sides being painted black to thereby increase heat transfer from the interior of the hover to directly under the painted portions.

4. A brooder of the class described, comprising an elongated compartment, an elongated hover medially positioned within said compartment and having means whereby the hover may be raised and lowered manually, heating means within said hover, said raising and lowering means comprising two transversely positioned stationary rods, said rods being positioned a distance above said hover and in substantially the vertical planes with the ends of said hover, fabric strips secured to the ends of said hover overlying said rods and then extending in the same direction for a short distance, metal reinforcing means secured to the free ends of said fabric strips, a rod forming a connection between said reinforcing means and a spring secured to one of said reinforcing means and being anchored to the end wall of said compartment to thereby counterbalance the weight of said hover, and a cranked rod being screw threaded to one of said reinforcing means, the end adjacent the crank being rotatably and slidably extended through the end wall of said compartment and having means whereby said crank may be turned to determine the vertical position of the hover.

5. A brooder of the class described, comprising an elongated compartment, an elongated hover medially positioned within said compartment and having means whereby the hover may be raised and lowered manually, heating means within said hover, said raising and lowering means comprising two transversely positioned stationary rods, said rods being positioned a distance above said hover and in substantially the vertical planes of the ends of said hover, belts secured to the ends of said hover overlying said rods and then extending in the same direction for a short distance, metal anchors secured to the free ends of said belts, a rod forming a connection between said metal anchors, and a cranked rod being screw threaded to one of said anchors, the end adjacent the crank being rotatably extended through the end wall of said compartment, whereby said crank may be turned to raise or lower said hover.

6. A brooder of the class described, comprising

ing an elongated compartment, an elongated hover medially positioned within said compartment, heating means within said hover, raising and lowering means comprising two transversely positioned stationary rods, said rods being positioned a distance above the ends of said hover and in substantially the vertical planes of the ends of the hover, fabric strips secured to the ends of said hover overlying said rods and then extending in the same direction for a short distance, metal reinforcing means secured to the free ends of said fabric members, a rod forming a connection between said reinforcing means, and a cranked rod being screw threaded to one of said reinforcing means, the end adjacent the crank rotatably and slidably extending through an end wall of said compartment whereby said crank may be turned to determine the vertical position of the hover and pulled to temporarily raise the hover.

7. A battery brooder of the class described,

comprising a number of compartments positioned one above another, a hover comprising an inclosure positioned in each of said compartments, said hovers each having a burner and being adapted to act as combustion chambers for the burner, means for independently manually raising and lowering the hovers, a vertically arranged chimney positioned adjacent said compartments and having separate duct connections 10 to each of said hovers for the escape of the products of combustion, and a vertically enlarged opening in one side of each of said compartments through which said ducts extend, the ends of said ducts being loosely fitted into the chimney, and hovers to thereby cooperate with said enlarged openings to permit free vertical movement of said hovers.
